(57) **CLAIM**

I claim the ornamental design for a solar bicycle safety light, as shown and described.

DESCRIPTION

FIG. 1 is a side elevation view of the solar bicycle safety light, mounted in place on the seat post of a bicycle and rotated to have the emitted light facing rearward, with the arrow indicating that the light-emitting element can be rotated;

FIG. 2 is a top plan view of the solar bicycle safety light, shown with the light-emitting element facing downward;

FIG. 3 is a rear view of the solar bicycle safety light of FIG. 5;

FIG. 4 is a side elevation view of the solar bicycle safety light of FIG. 2;

FIG. 5 is a bottom view of the solar bicycle safety light of FIG. 2;

FIG. 6 is a side elevation view of the solar bicycle safety light of FIG. 2;

FIG. 7 is a front view of the solar bicycle safety light of FIG. 5;

FIG. 8 is a side elevation view of the solar bicycle safety light, mounted in place on the handle bars of a bicycle and rotated to have the emitted light facing forward, with the arrow indicating that the light-emitting element can be rotated;

FIG. 9 is a top plan view of the solar bicycle safety light, shown with the light-emitting element facing downward;

FIG. 10 is a rear view of the solar bicycle safety light of FIG. 12;

FIG. 11 is a side elevation view of the solar bicycle safety light of FIG. 9;

FIG. 12 is a bottom view of the solar bicycle safety light of FIG. 9;

FIG. 13 is a side elevation view of the solar bicycle safety light of FIG. 9; and,

FIG. 14 is a front view of the solar bicycle safety light of FIG. 12.

The broken line showing of environment in FIG. 1 and FIG. 8 is included for the purpose of illustration only and forms no part of the claimed design.
